METHOD OF MOLDING A WALL STRUCTURE Walter L. Wood, 1602 Unit D, N. Harper,
Santa Ana, Calif.Filed Jan. 9, 1961, Ser. No. 81,397
2 Claims. (Cl. 264—259)

This invention pertains to new and improved manufacture of wall constructions.

For many years it has been customary to "build up" a waterproof wall in a shower, around a bathtub or various other types of locations from the materials used in such walls. Thus, for example, many shower stalls have been created by applying ceramic or other tile to a desired location within a building. This type of general procedure is considered to be unduly expensive for present day conditions. To a large extent such expense is a result of the fact that considerable time is required in order to erect a tile or similar wall and of the fact that the rates paid labor for such work are comparatively high.

It has been realized in the past that one manner of overcoming the problem of the high cost of waterproof or water resistant walls within buildings would be to manufacture such walls in a factory where mass production techniques and the like permit the use of comparatively inexpensive materials and permit the use of comparatively unskilled labor. Unfortunately conventional materials as used in showers around bathtubs and the like do not readily lend themselves to complete prefabrication in a factory.

As a result of this, various efforts have been made to develop the use of various newer materials for use in showers or other similar walls. Thus, for example, at the present time it is known to form flat wall panels out of various known materials and to join these panels together on a job site through the use of various types of waterproof or water resistant fittings. This approach to the problem of lowering costs is considered to be only partially successful because of the costs involved in creating and using such fittings and because of the fact that frequently problems are encountered with them as a consequence of various parts not fitting together in the desired manner and as a consequence of the fact that not infrequently such fittings are used so that waterproof joints are not achieved.

It has been realized for some time that the techniques employed in building various types of structures such as boats could be utilized in creating complete shower or similar constructions in which no joints between individual wall panels and sections would have to be created on a job site. Unfortunately, however, polymer compositions such as are employed with these techniques esthetically do not appear to be overly desirable. The acceptability of any wall structure to a large extent is determined by its appearance as well as by various cost considerations.

The present invention has, as one of its objectives, new and improved manufacture of wall constructions by utilizing polymer compositions in conjunction with other materials so as to provide structures having esthetically desirable characteristics. Another objective of this invention is to mold wall constructions for showers and other related purposes which do not employ joint susceptible of leaks between individual wall panels or areas. A further objective of this invention is to mold wall constructions which may be easily and conveniently formed at a comparatively nominal cost and in which a composition board is used for esthetic as well as utilitarian purposes as hereinafter described. A still further object of this invention is to provide a new and improved method for creating wall constructions as herein described either

2

alone or in combination with various functional parts of a structure such as a shower stall.

These and various other objects of this invention as well as many specific advantages of it will be more fully apparent to those skilled in the art to which this invention pertains from a detailed consideration of the remainder of this description including the appended claims and the accompanying drawings in which:

FIG. 1 is a perspective view of a shower stall construction in accordance with this invention;

FIG. 2 is a vertical, cross-sectional view taken at line 2—2 of FIG. 1;

FIG. 3 is an enlarged fragmentary view, in section, showing a part of the structure indicated in FIG. 2; and

FIG. 4 is an enlarged fragmentary view corresponding to FIG. 3 illustrating certain details in forming a structure as shown in the preceding figures.

The shower stall shown in the accompanying drawings is at this time considered to be a preferred product of the present invention. Those familiar with the field to which this invention pertains will realize, however, that the basic principles of this invention are not limited to shower stalls formed precisely as shown or even to shower stalls. Thus the features of the invention, as set forth in the appended claims, can be embodied within other structures than the precise structure shown through the use or exercise of routine engineering skill or ability.

As an aid to understanding this invention it can be stated in essentially summary form that in its broadest aspects it concerns wall constructions including a board member having a back side supported by a polymer composition which engages and surrounds the edges of such a board member and which extends from such a board member as essentially a border. This type of structure may be conveniently created by locating a board member on a mold corresponding to the final shape of a wall construction desired and then covering both the mold and the edges of the board member with a polymer composition and, then curing this composition so as to form a unitary structure which is, of course, removed from the mold.

The actual details of this invention are best explained by referring directly to the accompanying drawing. In these drawings there is shown a complete shower stall 10 of the present invention having vertically disposed walls 12 and a bottom shower pan 14. These walls 12 and the shower pan 14 have attached edges 16 which form waterproof joints in the complete stall 10. The shower pan 14 preferably includes a known type of central type drain opening 18 and an upstanding edge ridge 20 which extends around the portions of the shower pan 14 not attached to the walls 12. Preferably a small flange 22 is located on the side of the ridge 20 remote from the center of the pan 14 in such a location that it may be readily covered by flooring materials, a glass enclosure for the stall 10 (not shown) or the like. Similar edge flanges 22 are located on the unattached edges of the walls 12.

The construction of these walls 12 is considered to be extremely important with the present invention and is best seen by examination of FIG. 3 of the drawing. Each of the walls 12 includes a central composition board 24 and what is termed a "panel" 26 formed of a polymer composition. In a wall 12 the board 24 utilized is preferably formed in a known manner of exfoliated and then compressed fibrous material such as, for example, wood material, sugar cane bagasse or the like. Frequently various bonding agents of a known type are included in such composition board for the purpose of securing the individual fibers together. As so formed the board 24 has front and back sides 28 and 30 respectively which are connected by means of side edges 32. In practicing this invention preferably the side edges 32 are tapered or

sloped away from the front side 28 as indicated in FIG. 3 so that the back side 30 is slightly smaller than the front side 28.

Inasmuch as a composition board such as the board 24 is somewhat susceptible to the effects of water and is not considered to have a desired type of decorative appearance preferably the front side 28 is coated by means of a thin layer 34 of a water impervious material. A number of different known coating materials for providing the layer 34 are known at the present time. Preferably the layer 34 is composed of a melamine resin or similar resin composition which is laminated to the front side 28 by an appropriate conventional adhesive (not shown). The layer 34 may of course be provided with any sort of a decorative appearance desired, in accordance with known, conventional practice.

In the walls 12 the panels 26 covering the boards 24 are preferably formed of a water impervious polymer composition having a reasonable amount of structural rigidity. In the particular stall 10 illustrated the panels 26 are formed of the same material as the shower pan 14 so that the entire stall 10 is one integral, self-supporting unit which may be readily transported from a factory to a building where this stall 10 is to be installed. Although a number of different polymer compositions may be utilized in order to achieve this type of construction it is presently preferred with the present invention to utilize what is commonly referred to as a "fiberglass" composition.

Such fiberglass compositions are well known at the present time. They are composed of a polymerized polymer composition material such as a polyester resin containing reinforcing fibers such as glass fibers.

Polymer composition materials of this type are described in a number of different texts and other trade literature readily available at this time. In this connection reference is made to the book "Vinyl and Related Polymers" by Schildknecht, John Wiley & Son, Inc., New York, 1952 and Modern Plastic Encyclopedia issue for 1961, September 1960, vol. 38, No. 1A, published by Breskin Publications, Inc., 575 Madison Avenue, New York, New York for additional information with respect to this type of polymer composition and polymer composition materials used in the same.

The panels 26 utilized preferably include as a part of these panels a so-called "gel coat" 36 located on their normally exposed surfaces within the complete shower stall 10. Such a gel coat is a comparatively thin layer of a polymer composition material such as polymer composition material utilized within the body of the panels 26. In effect, the gel coat 36 is of the same character as the body of any of the panels 26 but does not contain a reinforcing material such as fiberglass as indicated in the preceding. As used in the stall 10 the gel coat 36 overlays the front sides 28 of the boards 24 a short distance so as to, in effect, define a lip like margin or small boarder 37 directly upon each of the boards 24. Further, the gel coat 36 preferably engages the side edges 32 substantially as indicated in the drawings so as to protect these side edges and so as to establish a structure capable of physically holding the board 24 in place.

For the purpose of providing additional reinforcement against bending of the panels 26 it is preferred to locate against the back surfaces of the boards 24 elongated channels 38 having a generally hat-shaped cross-sectional configuration. These channels 38 include side flanges 40 which rest against the back sides 30 of the boards 24. These channels 38 are, in the stall 10, held in place by the material within the panels 26 overlaying them and physically hold them against the boards 24. As shown the panels 26 extend along the entire back sides 30 of the boards 24 in order to reinforce these boards and in order to protect them against moisture or the like.

In considering the preceding it will be realized that the panels 26 utilized extend completely around each of the

boards 24 so as to, in effect, define a complete border around each of these boards. It will also be realized that the panels 26 have front surfaces which are substantially contiguous to the front side 28 of the boards 24. With this type of construction each of the walls 12 is of a substantially flat configuration such as is normally desired within a building. It will be realized, however, that the type of construction employed in a wall 12 can be utilized with boards such as the boards 24 which are curved to any desired shape for esthetic and/or appearance reasons.

The entire shower stall 10 may be easily and conveniently created using a technique which is best described by referring to FIG. 4 of the drawings. In preparing the stall 10 a mold 50 is preferably prepared so as to have a smooth external surface 52 corresponding to the interior or normally exposed shape of the surface of a shower stall such as the stall 10. As the mold 50 is utilized it is preferably located in a vertical manner so that a portion 54 of it corresponding to the pan 14 is located at the top of it and so that walls 56 corresponding to the walls 12 are located vertically. After being so located the mold 50 is prepared for use by being coated with a known type of mold release agent such as a wax composition or the like.

Next in creating a stall such as the stall 10 the boards 24 utilized are located upon the walls 56 in positions corresponding to their final positions within a stall shower. These boards 24 may be held in place in several different manners. In carrying out the present invention, however, it has been found to be advisable to secure them to the walls 56 through the use of pressure sensitive adhesive tape 58. Both sides of this tape 58 are coated with an adhesive so that the tape 58 may be located as shown in FIG. 4 to extend between the walls 56 and a board 24.

A tape such as the tape 58 serves to space a board 24 from a wall 56 so as to allow formation of the small lip 37 of a gel coat 36 as previously indicated during the fabrication of a complete stall 10. Further, a tape such as the tape 58 serves to prevent unwanted resinous material from extending in an undesired or irregular manner over the entire front side 28 of a board 24 during subsequent steps as hereafter described.

In order to prevent buckling of a board 24 upon the mold 50 it is preferred to locate within this mold 50 a series of regularly spaced small air holes 60, on the portions of a wall 56 normally covered by a board 24. Such air holes 60 will prevent air from being entrapped beneath a board 24 upon a wall 56 as such a board is being located in place, and will prevent the development of air pockets should this mold be subsequently heated in order to create a rigid structure.

After locating a board such as the board 24 in place upon the mold 50 it is preferred to position upon the back side 30 of such a board a channel such as the channel 38 previously described. Such a channel 38 may be easily held in place through the use of various known adhesives or by merely taping it in place with small sections (not shown) of known pressure sensitive tape.

After these operations are complete it is preferred to apply to the mold 50 a liquid or similar polymer composition material capable of forming the so-called "gel" coat 36 previously referred to. When such a material is sprayed upon the mold 50 it will adhere to the surface of this mold to a sufficient extent so that it will not run off of it. Further, such a liquid material will similarly adhere to the contacted portions of the board 24 in order to establish a satisfactory type of seal when the polymer composition material composing this coat 36 is subsequently polymerized. After this step the entire panel 26 may be easily and conveniently created by applying to all exposed areas of the mold 50 a mixture of polymer composition material and reinforcing fibers. Such a mixture may, of course, be sprayed in place although if desired various hand "lay up" procedures may be used. At this point all that remains to create a complete stall 10 is to

cause polymerization of the plastic material or materials used.

Normally such a plastic material is applied to the mold surface 52 together with an appropriate type of catalytic agent capable of causing it to "set up" at room temperature after a reasonable period. Such agents are, of course, well known. If desired, however, other methods of polymerizing the polymer composition material such as by the application of heat may be employed. After such polymerization is complete the entire stall structure is comparatively rigid; it is, of course, removed from the mold 50 prior to use. In such a structure the polymer composition material is satisfactorily bonded to both the front side 28 and the edges 32 of the boards 24 so as to provide water tight seals or joints protecting against the effects of water. The particular slope of the edges 32 employed aids in achieving a satisfactory holding and sealing action achieved. This slope is also desirable inasmuch as it facilitates the edges 32 being bent or deformed slightly if this should be necessary to compensate for any mold irregularities.

Those skilled in the art to which this invention pertains will realize that the techniques described in the preceding can, of course, be applied to creation of bathtubs and various other types of structures and that these techniques can be applied to the manufacture of various types of flat decorative panels. They will further realize that wall constructions as herein described are very advantageous from a commercial as well as a utilitarian sense, and that these wall constructions offer a number of distinct advantages over prior related structures.

I claim:

1. A process for forming a wall construction which includes the steps of: coating a mold having a shape corresponding to the shape of a surface of said wall construction with a release agent; coating the front side of a composition board with water impervious material; locating a composition board on said mold, so that the water impervious material on the front side of said board is ad-

30

35

40

jacent to said mold; covering said composition board and said mold away from said composition board with a polymer composition including polymer composition material and reinforcing fibers; curing said polymer composition material so as to create a rigid structure upon said mold and so as to bond said polymer composition material to said reinforcing fibers and to said board; and removing the so-cured polymer composition material and said board from said mold.

2. A process for forming a wall construction which includes the steps of: coating a mold having a shape corresponding to the shape of a surface of said wall construction with a release agent; coating the front side of a composition board with water impervious material; locating a composition board on said mold with a member located between said composition board and said mold defining a border spaced from the edges of said composition board, so that a front side of said board is adjacent to said mold; locating a polymer composition material within said border and along the surface of said mold not covered by said composition board, covering said mold and said composition board with a polymer composition including polymer composition material and reinforcing fibers; curing said polymer composition material so as to create a rigid structure upon said mold and so as to bond said polymer composition material to said reinforcing fibers and to said board; and removing the so-cured polymer composition material and said board from said mold.
